8 Claims. (Cl. 223—68)

1

The present invention relates to a lay figure and more particularly to a lay figure of which the lateral portions located between the breast and the back are contractable or collapsible on to a central fixed portion, so as to enable a reduction to be made in the perimeter corresponding to the line of the shoulders and bust, down to a size close to that of the waist line of the lay figure. Lay figures as hitherto used by tailors and dressmakers had the portion corresponding to the thorax of the human body constructed as a rigid whole and generally cushioned or upholstered.

The steps which a dressmaker had to perform in making a garment were, first, to cut out the several constituent portions of the garment according to the pattern, then to place such portions on the lay figure and join the corresponding edges of the several seams by means of pins. The ideal arrangement would have been if thereupon the garment thus assembled could have been removed from the lay figure without having to remove the pins connecting the several margins of the seams. However, up to the present such a course has been impossible in almost all cases, since, particularly in the case of women's garments such garments must generally be narrow at the waist which has a smaller perimeter than the portion corresponding to the shoulders or bust, for which reason it was obviously not possible to remove the assembled garment from the lay figure. Hence it was necessary to mark with chalk the points of connection of the seams provisionally formed by the pins, as well as the width of the hem of one margin of the seam on the other; thereupon, to disassemble the garment, remove the several component portions from the lay figure and reassemble the garment on a cutting table or other suitable support.

Due to the fact that the line of chalk has a certain thickness, for the reassembly of the aforementioned component parts on a table, the services of an expert are required since small displacements of the seams lead to faults which are clearly visible once the garment has been finished. The garment in the making, after being reassembled, is stitched. Before the seams are definitely sewn together, the person for whom the garment is intended, must try it on to check such mistakes in the joining of the seams as may have been made during the reassembly of the garment. The garment cannot be tried on the lay figure for the reasons above set forth, that is to say, due to the fact that the perimeter of the waist line is too small for it to pass over the shoulders of the lay figure. On the other hand,

2

a living person can try the garment on because such person may contract and/or displace forwardly his or her shoulders whereby to reduce the spread thereof. When women are concerned, a hunching together of the shoulders also reduces the perimeter of the bust-line.

With the lay figure in accordance with the present invention, the difficulties encountered with conventional figures are overcome by inclusion in the novel construction of articulations which permit the shoulders and bust to be actuated so as to reduce the perimeter thereof in imitation of the movements performed by the human body for contracting said parts.

15 Consequently, the present invention consists essentially in a lay figure having a body portion which includes at least a portion corresponding substantially to a human trunk in which the parts corresponding to the side portions extending from the waist line to the shoulders are contractable or collapsible, whereby the required reduction in perimeter of the lay figure is obtainable so as to permit both the fitting on and the removal of the corresponding garment.

20 25 From the foregoing, it will be seen that the present invention has a number of objects, one of the principal objects being to provide a novel lay figure capable of imitating the movements of the human body for hunching up the shoulders and the bust.

Another object is to provide an efficient lay figure which shall be simple to construct, easy to manage and of relatively low cost, so as to place it within reach of the small dressmaker.

30 35 A further object of the present invention is to allow of the garments which have been assembled on the lay figure to be removed therefrom without first disassembling the provisional seams made in the garment.

40 Another object is to enable the garment to be fitted onto the lay figure as many times as may be necessary during the making thereof, for the correction of any defects which may occur during the making of the garment.

45 50 A still further object is to enable finished garments to be placed on the lay figure for exhibition purposes whereby, due to the adjustability of the perimeter of the shoulders and bust it is possible to obtain a perfect fit of the garment on the lay figure. In this way the lay figure will display the original form and shape of the garment and the latter will not require correction to adapt it to the shape of the lay figure by the use of either pins or other known means.

55 Other objects and advantages of the present

invention will become apparent in the course of the following detailed description of a preferred embodiment thereof which has been illustrated by way of example in the accompanying drawings, in which:

Figure 1 is a perspective view of the lay figure in its normal condition, the broken lines representing the contracted or collapsed position thereof.

Figure 2 is a perspective view of the frame-work of the lay figure from which the actuating mechanism and the outer soft covering have been omitted.

Figure 3 is a front elevation partly in section of the actuating mechanism of the lay figure, certain parts of the frame work thereof having likewise been shown.

Figure 4 is a side elevation partly in section along the line 4—4 of Fig. 3 of the lay figure of the invention, in which parts of the actuating mechanism and parts of the frame work of the lay figure have been omitted.

Figure 5 is a detail of the actuating mechanism partly in longitudinal section.

Fig. 6 is a plan view taken on the plane 6—6 of Fig. 5.

In the several figures, the same reference characters indicate like or corresponding parts. Devices or elements comprising several parts are indicated by reference letters. As may be seen in the drawings and particularly in Figs. 1 and 4, *a* is the body of the lay figure, the framework of which may be of cardboard, wood, sheet-metal or any other suitable material, the whole being covered on the outside with a quilted cloth *1* formed by an outside layer *2*, an inner, stronger layer made of commoner material *3*, and cotton or the like *4* which fills the space between said two layers so that the whole forms a quilted assembly or cover *1*.

The framework *b* of the lay figure *a* illustrated in Fig. 2 forms one of the main features of the present invention. The several component parts thereof must be so shaped and arranged as to permit the perimeter of the shoulders *53* and *54* and of the bust of the lay figure to be reduced to about the size of the waist line. To this end a roughly frusto-conical portion *5* is used to form the part corresponding to the abdomen of the human body. The major end *6* or base of the frusto-conical part *5* corresponds more or less to the height of the iliac crest, that is to say a little higher than the fork of the human body. The smaller end *7* indicated by a chain line corresponds to the waist. From said smaller end the several parts of the frame forming the trunk *c* of the lay figure *a* extend. These parts are designed to imitate as far as possible the constitution of the skeleton of the human body. Thus, in the rear portion a member *8* extends which represents the spine and thus forms the portion sustaining the back *9* of the lay figure *a*. Said member *8* is of width substantially greater than that of the human spine. In the upper part corresponding to the collar-bones said member *8* is curved forwardly forming roughly a spherical triangle *10* which represents the breast bone and part of the ribs which extend therefrom, the vertex *11* of said triangle being downwardly directed and terminating at approximately the height of the xiphoid appendage of the sternum. In the upper part of the member *8* where the curves *12* and *12'* are formed, the neck portion *13* rises, which portion has in the forward or front part thereof three

holes *14*, *15* and *16*, the last named being of greater diameter than the other two. The upper edge *17* has a notch *18* which may be semicircular in shape and is arranged to lie in substantially the same vertical transverse plane as the central hole *16*. For proper operation of the lay figure *a* according to the present invention, it is an essential condition that the longitudinal edges *19* and *20* of the rear portion *21* of the member *8* be vertical and substantially parallel.

From the small end *7* of the frusto-conical member *5* there likewise extends, but in the front part thereof, another member *22* having roughly the form of a spherical triangle, the apex *23* of which is at approximately the height of the umbilicus in the human body.

In Fig. 4 may be clearly seen the curvatures of the back which the member *8* must have in order to imitate as closely as possible the shape of a human back when at rest. It should be added that the rear part of the neck portion has another perforation *26* the purpose of which will be hereinafter explained.

Referring now again to Fig. 2, it may be seen therefrom that the side members *24* and *25* likewise extend upwardly from the small end *7*. Since the side members *24* and *25* are substantially equal and symmetrical, reference will now only be made to the side member *25*, it being understood that all the features about to be explained hold as well for the side member *24*.

The side members do not extend only over the spaces comprised between the front portion formed by a part of the abdomen and the breast, and the back, but likewise form the framework of the two breasts and the part corresponding to the acromial and caracoid processes which form part of the shoulder. In order to facilitate the understanding of the exact shape of each of the two side members the member *25* has been subdivided into three zones namely the front zone *e* included between the front edge *27* and the auxiliary dotted line *28*, the flank zone properly so called *e*, formed between the auxiliary dotted line *28* and the false edge *29* formed between the so called flank zone *e* and the rear zone *f*, said rear zone being defined by said edge *29* and the other true edge *30* indicated by a chain line, said third portion or rear zone *f* forming a part of the back of the lay figure.

The front edge *27* has a lower portion extending from the angle *31* of the spherical triangle *22* and having a curve *32* which is complementary to the side *33* of the spherical triangle *22* and is upwardly directed. Said curved portion *32* is in the part corresponding to the bust shaped like the curve of the intersection of the breast with the flat portion corresponding approximately to the breast-bone, that is to say the space *34* between the two edges *32* of the two side members *25* and *24* would correspond to the hollow which separates the breasts. The point *35* indicates approximately the apex of the cone formed by the breast.

The rear edge *30* likewise originates at the height of the smaller end *7* as a complementary line of the curve *20* of member *8*.

It is necessary that both the line *32* and the line *30* form at their origins curves which are complementary to their respective members *8* and *22* and there must be an intermediate space *36* and *37* respectively between said members in order that when the shoulders *53* and *54* are brought into contracted or collapsed position the

movable side members do not overlap the fixed members, as this would occasion the formation of bumps or the catching of materials and other difficulties in the proper operation of the lay figure *a*.

The actuating mechanism *g* of the lay figure *a* illustrated in Fig. 3 is of simple construction and easy to operate. It consists of two cross members 38 and 39 which are transversally disposed as may be seen in Fig. 4, the member 38 being arranged at the level of the small end 7 and the member 39 below the base of the neck 13. On the side faces 40 and 41 of the cross member 38 and the side faces 42 and 43 of the cross member 39, lateral reinforcements 44 and 45 respectively are mounted, the reinforcement 45 being omitted from Fig. 4 for clearness. Said reinforcements 44 and 45 likewise form supports for compression springs 46 and 47 respectively. Said springs 46 and 47 are secured at their ends 48 and 49 by means of clamps 50 to the reinforcements 44 and 45 respectively. The other ends 51 and 52 of the springs 46 and 47 freely engage the inner face of the side members 25 and 24 at the level of the shoulders 53 and 54 of the lay figure *a*. In order to prevent downward displacement or slipping of the ends 51 and 52 of the springs 46 and 47 stop screws 55 and 56 are screwed into the shoulders 53 and 54 at a suitable height in the side members 25 and 24.

A pin 57 passes vertically from below upwardly through the cross member 39, the end 58 of said pin projecting therebeyond for a distance at least equal to twice the diameter of the arbor 62. The head of the pin 59 does not directly engage the lower face 60 of the cross member 39 but a washer 61, preferably of metal, is interposed in order to prevent the head 59 of the pin 57 from biting into the wood of the cross member 39. The arbor 62 has a central perforation 63 in which the free portion of the pin 57 fits so that the arbor 62 may rotate on said pin 57, the lower end 64 of said arbor 62 resting on the upper face 65 of the cross member 39.

To enable the side members 25 and 24 to be moved to a contracted or collapsed position, each has a tension member or strap 66 and 67 secured to it by screws 68 at the level of the shoulders 53 and 54. The other ends 69 and 70 of said straps or tension members 66 and 67 are suitably secured to the arbor 62 so that on rotation of said arbor 62 the tension members 66 and 67 are wrapped therearound, thereby exerting a pull on the shoulders 53 and 54 to bring the same closer to the arbor 62. To effect this operation it is necessary to overcome the thrust of the springs 46 and 47.

On the edge 11 of the neck 13 rests a flange 73 of the cover 71 (see Fig. 5) provided with a central bore 72 and a frusto-conical portion 74 which fits into the interior of the neck 13. The arbor 62 passes through the central bore 72 and has mounted thereon immediately below the lower edge 75 of the cover 71 a ratchet wheel 76 which is secured in position on the arbor 62 by means of a key 77.

Returning now to the cover 71 it may be seen that immediately below the flange 73 there is a bush 80 which passes through the frusto-conical portion 74 up to the central bore 72, the end 81 projecting beyond the flange 73. Said end 81 engages in the notch 13 of the neck 13. Diametrically opposite the perforation corresponding to the bush 80 but slightly lower down there is another perforation 82 which registers with the hole 76 when the cover 71 is in position on the neck 75.

13. The cover 71 is secured to the neck 13 by means of a fixing screw 83 which passes through the hole 26 in the neck 13 and is screwed into the tapped bore 82 of the cover 71. For locking the ratchet wheel 76 we provide a U shape detent 84, the arm 85 being inserted in the bush 80 whereas the other arm 86 passes through a plate 87 provided with a central perforation 88 registering with the hole 16 of the neck 13, said plate 87 being fixed to the neck 13 by two fixing screws 89 and 90 (see Fig. 1) passing through the holes 14 and 15 of neck 13. Close to the end of the arm 86 a collar 78 is secured, and a compression spring 92 is mounted between said collar 78 and the inner face 93 of the neck 13, said spring 92 maintaining the detent 84 properly so called, which is pointed, in engagement with the ratchet wheel 76. In order to actuate the detent 84 the part 91 which is accessible from outside is pulled, the detent 84 returning to its original position after release of the effort applied to overcome the force of the spring 92. For rotating the arbor 62 we provide a knob 96 concentrically mounted on the upper end 97 of said arbor 62. One of the cheapest and most practical ways of securing the knob 96 to the arbor 62 is shown in Figs. 3 and 5. It consists in providing the upper end 97 of the arbor 62 with a vertical diametral incision and in mounting on the knob 96 a plate 94 which divides the central recess 95 of said knob 96 into two halves, said plate being inserted in the incision as shown in the aforementioned figures. In this way the knob 96 may be rapidly mounted and dismounted and if required may be replaced as for example by a wax head or the like. Obviously such a head may not be used for actuating the arbor 62 but it is very convenient to be able to fit such a head should it be desired to use the lay figure for display purposes. It will however be understood that the several members of the actuating mechanism *g* can be constructed in many other ways, once the inventive idea herein disclosed has been understood.

The method of actuating the lay figure is very simple. For this purpose, it should be recalled that the object is to obtain a narrowing of the shoulder and bust width of the lay figure so as to be able to clothe and unclothe the same with garments which are a close fit at the waist. In other words, the maximum perimeter which generally corresponds to the shoulders must be reducible to at least that of the waist.

On rotating the arbor 62 by means of the knob 96 the tension members or straps 66 and 67 are shortened whereby the side members 24 and 25 are brought closer together and the force of the springs 46 and 47 is overcome. The ratchet wheel 76 and the detent 84 hold the side members 24 and 25 in the new position. The broken lines of Fig. 1 indicate the collapsed or contracted position of the lay figure *a* and it will be seen that the shoulders 53 and 54 enter into the curves 12 and 12' of the member 8. In the broken line or collapsed position of the lay figure three folds are chiefly caused, two, namely the folds 98 and 99, owing to the contraction of the side members, and a central fold 100 which is the remainder of the distance 34, that is to say it represents the distance between the breasts when a woman hunches up her shoulders and thus displaces the breasts forwardly. Since the part corresponding to the edges 32, that is to say the part corresponding to the breasts of the framework, are completely free, the imitation breasts may, if necessary, be pushed in whereby the perimeter corre-

sponding to the bust is still further reduced. On completion of the operation of clothing or unclothing the lay figure, it is merely necessary to give a slight turn to the knob 96 in the direction for collapsing the side members, draw out the detent 64 for which purpose a finger is hooked into the part 95 of the detent, and allow the springs 46 and 47 to act to restore the side members to their original positions, so that the lay figure a will again be in the position indicated in the full lines in Fig. 1.

As a modification of the invention herein described it may be said that by means of a mechanism similar to that used for actuating the side members the breasts may also be collapsed if this is thought convenient. In such event the second operating mechanism may be independent or may be designed to act in combination with the mechanism herein described so that a single control means would be required for actuating both moving parts. It will be obvious that in such event the breast actuating springs would have to be located perpendicularly to the springs 46 and 47.

If the lay figure is to be used for display purposes the knob 46 may, as has already been indicated, be replaced by a head of wax or other similar material. Furthermore, arms may be attached to the parts corresponding to the shoulders, to which end the shoulders would have to be provided with plates, to which the arms may be coupled in a manner well known to those skilled in the art. Since the lay figure illustrated is hollow, parts corresponding to the lower extremities may be inserted into the lower portion of the lay figure to which end the cross member 38 may be utilized as a fixing means.

From the foregoing description, it will be clear that the present invention is capable of a large number of applications from the point of view of working thereon or using the same for display purposes.

Furthermore, it is to be understood that in carrying this invention into practice we may make certain modifications as regards details of construction and form without however departing from the spirit and scope of the invention as defined in the accompanying claims.

We claim:

1. A one-piece lay-figure of resilient material comprising at least a part corresponding substantially to the human trunk, said part consisting of a waist portion having integral therewith two members of unbroken continuity with each of said members defining a flank portion, a partial shoulder portion and a half-chest portion, said half-chest portion extending transversely of the figure into close proximity of the vertical median plane thereof, said waist portion having also at its rear part an integral unbroken centrally disposed member extending upwardly for a distance substantially equal to the height of the back of the trunk involved and terminating at its end remote from the waist portion in an integral forwardly and downwardly bent portion of substantially spherical triangular shape having a free downwardly directed vertex situated above, but normally spaced away from said breast portions.

2. A one-piece lay-figure of resilient material comprising at least a part corresponding substantially to the human trunk, said part consisting of a waist portion having integral therewith two members of unbroken continuity, each of said members defining a flank portion, and a half-chest portion, said half-chest portion ex-

tending transversely of the figure into close proximity to the vertical median plane thereof, said waist portion having also at its rear part an integral unbroken centrally disposed member extending upwardly for a distance substantially equal to the height of the back of the trunk involved.

3. A one-piece lay-figure of resilient material comprising at least a part corresponding substantially to the human trunk, said part consisting of a waist portion having integral therewith two members of unbroken continuity, each of said members defining a flank portion, and a half-chest portion, said half-chest portion extending transversely of the figure into close proximity to the vertical median plane thereof, said waist portion having also at its rear part an integral unbroken centrally disposed member extending upwardly for a distance substantially equal to the height of the back of the trunk involved and terminating at its end remote from the waist portion in an integral forwardly and downwardly curved portion of substantially spherical triangular shape having a free downwardly directed vertex situated above but normally spaced away from said breast portions.

4. A one-piece lay-figure of resilient material comprising in combination at least one part corresponding substantially to the human trunk, said part consisting of a waist portion having integral therewith two members of unbroken continuity, each of said members defining a flank portion, and a half-chest portion, said half-chest portion extending transversely of the figure into close proximity to the vertical median plane thereof, said waist portion having also at its rear part an integral unbroken centrally disposed member extending upwardly for a distance substantially equal to the height of the back of the trunk involved; and a quilted cloth cover upon the whole of said lay-figure consisting of an outside layer, an inner layer of relatively tougher material than that of the outside layer, and a filler intermediate the outside and inner layers.

5. A lay-figure of resilient material comprising a waist portion; a one-piece back portion extending upwardly from the upper rear edge of said waist portion at a distance substantially equal to the back of a human trunk; and two oppositely arranged one-piece side portions, each of said side portions extending upwardly from one upper side edge of said waist portion and including forwardly curved breast portions, the adjacent marginal edges of said forwardly curved breast portions of said one-piece side portions defining a space therebetween, and each marginal edge of the one-piece back portion and the corresponding rear marginal edge of each of said side portions defining another space therebetween.

6. A lay-figure of resilient material comprising a waist portion; a one-piece back portion extending upwardly from the upper rear edge of said waist portion at a distance substantially equal to the back of a human trunk; two oppositely arranged one-piece side portions, each of said side portions extending upwardly from one upper side edge of said waist portion and including forwardly curved breast portions, the adjacent marginal edges of said forwardly curved breast portions of said one-piece side portions defining a space therebetween, and each marginal edge of the one-piece back portion and the corresponding rear marginal edge of each of said side portions defining another space therebetween.

tween; and means for turning said one-piece side portions substantially about the upper side edges of said waist portion toward each other so that said rear marginal edges of said one-piece side members are moved toward said marginal edges of said one-piece back portion and said adjacent marginal edges of said forwardly curved breast portions are moved toward each other.

7. A lay-figure of resilient material comprising a waist portion; a one-piece back portion extending upwardly from the upper rear edge of said waist portion at a distance substantially equal to the back of a human trunk; two oppositely arranged one-piece side portions, each of said side portions extending upwardly from one upper side edge of said waist portion and including forwardly curved breast portions, the adjacent marginal edges of said forwardly curved breast portions of said one-piece side portions defining a space therebetween, and each marginal edge of the one-piece back portion and the corresponding rear marginal edge of each of said side portions defining another space therebetween; and means for turning said one-piece side portions substantially about the upper side edges of said waist portion away from each other so that said rear marginal edges of said one-piece side members are moved away from said marginal edges of said one-piece back portion and said adjacent marginal edges of said forwardly curved breast portions are moved away from each other.

8. A lay-figure of resilient material comprising a waist portion; a one-piece back portion extending upwardly from the upper rear edge of said waist portion at a distance substantially equal to the back of a human trunk; two oppositely arranged one-piece side portions, each of said side portions extending upwardly from one upper side edge of said waist portion and including forwardly curved breast portions, the adjacent marginal edges of said forwardly curved breast portions of said one-piece side portions

defining a space therebetween, and each marginal edge of the one-piece back portion and the corresponding rear marginal edge of each of said side portions defining another space therebetween; first means for turning said one-piece side portions substantially about the upper side edges of said waist portion away from each other so that said rear marginal edges of said one-piece side members are moved away from said marginal edges of said one-piece back portion and said adjacent marginal edges of said forwardly curved breast portions are moved away from each other; and second means for turning said one-piece side portions substantially about the upper side edges of said waist portion toward each other so that said rear marginal edges of said one-piece side members are moved toward said marginal edges of said one-piece back portion and said adjacent marginal edges of said forwardly curved breast portions are moved toward each other.
